(57) **CLAIM**

The ornamental design for an exercise and training device, as shown and described.

DESCRIPTION

FIG. 1 is a top perspective view of an exercise and training device of our new design;

FIG. 2 is a bottom perspective view of the exercise and training device of FIG. 1;

FIG. 3 is a top view of the exercise and training device of FIG. 1;

FIG. 4 is a front view of the exercise and training device of FIG. 1 (the rear view being a mirror image of the view of FIG. 4);

FIG. 5 is a partial, bottom view of the exercise and training device of FIG. 1;

FIG. 6 is a left side view of the exercise and training device taken from the side shown in FIG. 5;

FIG. 7 is a partial, bottom view of the exercise and training device of FIG. 1, showing the portion of the exercise and training device not shown in FIG. 5; and,

FIG. 8 is a right side view of the exercise and training device taken from the side shown in FIG. 7.

The broken lines shown in FIGS. 5 and 7 define the location where the article is cut off to create the partial view and forms no part of the claimed design.
